WRAPPER SEALING MECHANISM FOR
PACKAGING MACHINES

Charles Areit, Richmond Hill, N. Y., assignor to
American Machine & Foundry Company, a cor-
poration of New Jersey

Original application February 20, 1940, Serial No.
319,864. Divided and this application June 17,
1943, Serial No. 491,123

3 Claims. (Cl. 93—27)

1

This invention relates to improvements in wrapper sealing mechanism for packaging machines, especially machines for the packaging of cigarettes and constitutes a division of my co-pending application, S. N. 319,864, filed February 20, 1940, for high speed cigarette packaging machines.

The invention particularly relates to packaging machines of the kind disclosed in the patent to W. B. Bronander, No. 1,926,192 issued September 12, 1933, in which the wrappers are folded about traveling mandrels, mounted for example on a rotary turret, to form containers closed at one end and open at the other end, into which the cigarettes or the like are inserted while still on the mandrels, the containers with the cigarettes or the like therein being ejected from the mandrels and the open ends of the containers then being closed to complete the packages.

The object of this invention is to provide improved means for sealing the folded end of the wrapper of each package or container in a more effective manner, and specifically to provide improved means for sealing the containers mentioned in the preceding paragraph prior to the insertion of the cigarettes or the like into the containers.

The invention consists in a wrapper sealing mechanism for a packaging machine provided with traveling hollow mandrels about the circumference and over one end of each of which a wrapper is folded, including a member adapted to engage the exterior of the folded end of the wrapper on a mandrel, and a member movable through the mandrel to press said folded end against said exterior member, one of said members having a convexly rounded rubber part arranged to press the folded end opposite the line of adhesives between the folded flaps thereof.

Other features of the invention will be clearly set forth in the claims appended hereto.

In the accompanying drawing:

Figs. 1 and 2 are respectively elevational and plan views of the plungers for sealing the bottom folds of the packages; and

Fig. 3 is a plan view of the additional plungers for setting the sealed bottom folds of the packages.

The present invention is especially applicable to packaging machines, particularly for packaging cigarettes, of the known kind such as disclosed in the above mentioned prior Patent No. 1,926,192 in which a support or turret intermittently rotated about a horizontal axis, is provided with a circular series of equally spaced apart hollow mandrels about which the wrappers, usually an inner metal foil wrapper and an outer paper wrapper or label sheet, are folded to form open-ended containers into which the cigarettes or other articles are inserted. In such machines,

2

an inner wrapper sheet is fed into position in front of a mandrel at one station of the rotary turret, usually the station at the top of the turret, and the wrapper is clamped against the mandrel by a movable clamp mounted on the turret. The turret advances the mandrel to another station, at which the wrapper is folded circumferentially about the mandrel, the overlapping edges of the wrapper being held in place by a rear or seam clamp movably mounted on the turret. At this or another station, the wrapper may be wholly or partially folded over one end of the mandrel. The turret advances the mandrel to another station, usually the station at 90° from the top of the turret, at which the front clamp is moved away from the mandrel and an outer wrapper or label sheet is positioned in front of the mandrel, the wrapper being then held against the mandrel by the front clamp. The mandrel is then moved to another station at which the rear clamp is moved away from the mandrel, and the outer wrapper is folded circumferentially about the mandrel and the inner wrapper thereon, the overlapping edges, one of which is provided with a stripe of paste, being then held by the rear clamp. At this or another station, the projecting end flaps of the outer wrapper and any unfolded flaps of the inner wrapper are folded over the end of the mandrel, the final flap being provided with paste to secure the folded end. A plunger, or successively acting plungers, inserted within the mandrel presses the folded end of the pouch or container against an exterior abutment, or abutments, to seal and set the same. At another station, usually diametrically opposite to the label delivery stations, a group of cigarettes or the like is inserted into the mandrel and thus within the pouch or container thereon. At a final station, usually the station at the top of the turret, the group of cigarettes or the like is ejected from the mandrel, and by engagement with the closed end of the pouch or container, strips the latter also from the mandrel, the filled container open at one end being moved into a position in line with a delivery guideway. In this position the flaps at the open end of the container are folded down over the group of cigarettes or the like and sealed, and the completed package is pushed into the delivery guideway. It will be understood that these operations apply to each mandrel in succession, and that a filled container is ejected from each mandrel as it reaches the position at the top of the turret.

Figs. 1, 2, and 3 illustrate one of the hollow open-ended mandrels M above referred to, which at its inner end is supported by a hollow block 320 which is secured to the rotatable support or turret. It may be assumed with respect to these figures that the wrapper at a preceding station 60 of the turret has been folded circumferentially

about the mandrel to form a pasted seam along one face of the mandrel, and that the flaps projecting beyond the outer end of the mandrel have been folded over to form the folded end, the outer or last folded end flap having had applied thereto a stripe or line of paste to provide for the sealing of the folded end. The end folding of the wrapper is disclosed in Patent No. 1,926,192 or the patent to G. W. Gwinn, et al., No. 1,885,910, issued November 1, 1932, and circumferential folding means are disclosed in my application S. N. 319,864, filed February 20, 1940, from which the present application has been divided.

At a station of the turret following the station at which the end folding is effected, a pair of movable plungers 321 and 322 are provided for effecting the sealing of the folded end of the container. The plunger 321 is moved through the mandrel to its outer end, and the plunger 322 is moved exteriorly toward the outer end of the mandrel, the folded end D of the container being pressed between the two plungers. The plunger 322 consists of a flat plate, but the plunger 321 carries a convexly rounded rubber cushion 323 arranged so that it is aligned with the paste line on the outer end flap of the outer wrapper. A flat plunger or rubber cushion would tend to become concave under the pressure and fail to properly press the seam, but the rounded cushion 323 actually concentrates the pressure at the desired point, namely along the paste line, and the pressure causes the paste to spread evenly between the bottom folds of the outer wrapper, thereby obtaining a superior bottom seal.

At a succeeding station, a second pair of plungers 324 and 327 are provided, as shown in Fig. 3. The interior plunger 327 comprises a flat plate, and the exterior plunger 324 is provided with a flat rubber cushion 325. These plungers press the folded end D of the container P between them, and provide a flat container bottom with square-shaped corners. Operating mechanism of generally known form may be provided for operating the two pairs of plungers, such for example as that disclosed in the above mentioned Patent No. 1,926,192. Thus a smooth bottom is assured on the package from which no folds will project to press inwardly against an individual cigarette and form a "white collar" thereon during the ejection of the package from the mandrel.

As in the known machines, a group of cigarettes or the like is inserted at a subsequent station into each mandrel, and thus within the partially formed container thereon, and as each mandrel reaches the ejecting station, usually the station at the top of the turret, the group of cigarettes or the like is ejected through the mandrel, stripping the container therefrom by engagement with the closed end thereof.

Each container with the cigarettes or the like therein is delivered to a mechanism for closing the open end of the container and delivering the same to a delivery guideway.

Having now particularly described and ascertained the nature of my said invention, and in what manner the same is to be performed, I declare that what is claimed is:

1. The combination with a hollow mandrel adapted to support a pouch formed of flexible sheet material and having end folds overlapped at one end of the mandrel to form the bottom of the pouch, the outermost end fold being provided with a stripe of adhesive on its inner face extending longitudinally of the pouch bottom, of an unheated plate movable into contact with the

exterior of the pouch bottom, a reciprocable member movable into the interior of the mandrel, said reciprocable member being provided with a semi-cylindrical groove, and a rounded rubber strip having a breadth which is no greater than the breadth of said groove, said strip being embedded in said groove in alignment with said adhesive stripe and adapted to be compressed against the interior of the pouch bottom when said reciprocable member enters said mandrel to seal the overlapped end folds together along said adhesive stripe, said rubber strip being considerably narrower than the breadth of said pouch bottom to concentrate the pressure applied by said rubber strip to a region of the pouch bottom extending along said adhesive stripe.

2. The combination with a hollow mandrel adapted to support a pouch formed of flexible sheet material and having end folds overlapped at one end of the mandrel to form the bottom of the pouch and provided with a stripe of adhesive on one of the end folds, said adhesive stripe being located between contiguous faces of the end folds and extending longitudinally of the pouch bottom, of an unheated member adapted to engage the exterior of the pouch bottom, a reciprocable member movable through the mandrel, one of said members being provided with a groove on its inner face, and a rounded rubber part whose breadth is no greater than the breadth of said groove, said rubber part being embedded in said groove and arranged to engage and press a portion of the overlapped end folds of the pouch bottom opposite said stripe of adhesive against the other of said members and thereby seal the overlapped folds, the breadth of said rounded rubber part being considerably narrower than the breadth of the pouch bottom to concentrate the pressure applied by said rubber part to a region of the pouch bottom extending along said adhesive stripe, a plunger adapted to enter the mandrel after the pouch bottom has been sealed by said members, said plunger being provided with a face having an area equal to the area of the pouch bottom and arranged to engage the interior of the pouch bottom, and a device for engaging the exterior of the pouch bottom for pressing it against said plunger face to flatten and square the pouch bottom.

3. The combination with a hollow mandrel adapted to support a pouch formed of flexible sheet material and having end folds overlapped at one end of the mandrel to form the bottom of the pouch and provided with a stripe of adhesive on one of the end folds, said adhesive stripe being located between contiguous faces of the end folds and extending longitudinally of the pouch bottom, of an unheated member adapted to engage the exterior of the pouch bottom, a reciprocable member movable through the mandrel, one of said members being provided with a groove on its inner face, and a rounded rubber part whose breadth is no greater than the breadth of said groove, said rubber part being embedded in said groove and arranged to engage and press a portion of the overlapped end folds of the pouch bottom opposite said stripe of adhesive against the other of said members and thereby seal the overlapped folds, the breadth of said rounded rubber part being considerably narrower than the breadth of the pouch bottom to concentrate the pressure applied by said rubber part to a region of the pouch bottom extending along said adhesive stripe.
